UNITED STATES PATENT OFFICE

JAN STRENG, OF NEW YORK, N. Y., ASSIGNOR TO THE ANSONIA CLOCK COMPANY,
OF NEW YORK, N. Y.

DESIGN FOR A TIMEPIECE HAND

Application filed December 29, 1928. Serial No. 29,447. Term of patent 3½ years.

To all whom it may concern:

Be it known that I, JAN STRENG, a citizen of the United States, residing at New York, in the county of New York and State of New York, have invented a new, original, and ornamental Design for a Timepiece Hand, of which the following is a specification, reference being had to the accompanying drawing, forming part thereof.

The figure is a plan view of a time piece hand, showing my new design.

I claim:—

The ornamental design for a time piece hand as shown.

Dated this 30th day of November, 1928.

JAN STRENG
